UNITED STATES PATENT OFFICE.

WILLIAM E. WHITE, OF CHICAGO, ILLINOIS, ASSIGNOR TO KALMAN STEEL CO., OF CHICAGO, ILLINOIS, A CORPORATION OF DELAWARE.

RIB CHAIR.

Application filed December 26, 1922. Serial No. 603,863.

To all whom it may concern:

Be it known that I, WILLIAM E. WHITE, a citizen of the United States, and resident of Chicago, in the county of Cook and State of Illinois, have invented certain new and useful Improvements in a Rib Chair, of which the following is a specification.

My invention relates to devices for supporting concrete reinforcements and particularly to a novel rib chair of simple and economical construction.

One of the objects of my invention is to provide a supporting device of the character described which shall be of utmost simplicity. To that end I construct the device from a single length of wire and so design the chair that it may be formed by automatic machinery. This results in extremely low cost.

20 A fundamental feature in the design submitted is in that I provide two **A** frames which furnish the required stability and join them by a member shaped to provide seats for reinforcing bars and located at the required height which will be at a point intermediate the height of the **A** frames. In addition I provide means for spacing the chairs relative to the sides of the forms which outline the lateral limits of the rib.

30 The invention will be more readily understood by reference to the accompanying drawing, wherein

Figure 1 is a perspective view of a rib chair constructed in accordance with my invention;

Figure 2 is an end view thereof;

Figure 3 is a perspective view of a modified form of the device;

Figure 4 is an end view thereof;

40 Figure 5 is a perspective view of a further modification; and

Figure 6 is an end view thereof.

In the drawings, referring particularly to Figures 1 and 2, it will be seen that in constructing the device of my invention I utilize a single continuous length of wire of suitable size and stiffness and form therein two **V**-shaped structures 10, 11, the legs 12, 13, of each of which rest upon a form and stabilize the structure. The wire at the termination of the legs 12 is re-bent and projects upwardly and longitudinally away from the leg, the members 14 constituting the re-bent portions projecting in opposite directions away from each other. At the

point 15 the wire is again re-bent, the portions 16 extending horizontally. The point 15 is so arranged as to constitute spacing means for the chair whereby to suitably center the chair and consequently the reinforcing bars within the rib. Intermediate the ends of the horizontal portion 16 I provide a loop 17 which may project upwardly or diagonally upwardly as shown. This results in the formation of pockets 18 for the accommodation of the reinforcing bars.

In the construction shown in Figures 3 and 4, the elements remain the same. However, the legs 19, 20, occupy different vertical planes, being spaced apart by means of a horizontal member 21. Thus the leg 20 acts as the means for centering the chair in the form. In this instance the re-bent portion 22 lies in the same plane with the leg 19. The horizontal part 23 and the loop 24 are the same as those heretofore described.

It will be noted that in each of the two structures described, the seat for the bar is located at a point substantially directly beneath the apex of the **A** frame and this lends stability to the structure.

In the construction shown in Figures 5 and 6, the legs 25, 26, are arranged the same as in Figure 1, being in the same plane. Likewise the part 27 is upwardly and longitudinally outwardly bent, the end 28 constituting the spacing device for the chair. However, the portion 27 is bent outwardly from the terminal point of the leg 25 instead of inwardly as in Figure 1. Thus the horizontal part 29 and the loop 30 which constitute the seat for the reinforcing bar are located outside of, instead of inside of the legs as in the two preceding figures.

45 In each of the structures described it will be noted that the same structural features are present and that the device is of such simplicity that it may be formed economically. By employing wire of suitable gauge and stiffness the required strength and stability are secured.

Obviously the construction is capable of some modification and I do not wish to be limited except as indicated in the appended claims.

I claim:

1. A rib chair composed of a continuous wire bent to provide two pairs of spaced-apart legs, each pair being arranged in **V**-shape, a connecting member located inter-

- mediate the height of the legs and providing a seat for a reinforcing bar, and, laterally projecting means for spacing the chair in a form.
5. A rib chair composed of a continuous wire providing two pairs of legs and a connecting member, said connecting member being arranged horizontally at a point midway of the height of the legs and shaped to 10 provide a seat for a reinforcing bar.
3. A chair consisting of a continuous length of wire bent to provide two pairs of legs, each pair of legs being arranged in V-shape, and a connecting member extending 15 between the pairs of legs and formed by rebending the wire upwardly from the ends
- of two of said legs, and means in the connecting member for providing a seat for a reinforcing bar.
4. A chair consisting of a continuous 20 length of wire bent to provide two pairs of legs, each pair of legs being arranged in V-shape, and a connecting member extending between the pairs of legs and formed by rebending the wire upwardly from the ends 25 of two of said legs, means in the connecting member for providing a seat for a reinforcing bar, and laterally projecting means for spacing the chair in a form.

Signed at Chicago, Illinois, this 20th day 30 of December, 1922.

WILLIAM E. WHITE.
